ELECTRIC PLUG

Benjamin F. Nauslar, San Diego, Calif.

Application April 4, 1947, Serial No. 739,339

3 Claims. (Cl. 173—332)

1

My invention relates to an electric plug, more particularly for use in connection with electric flat irons, coffee pots or other electrical appliances and the objects of my invention are:

First, to provide an electric plug of this class which when engaged with male plugs of a conventional electric flat iron or coffee pot firmly grips the prongs of said male plug preventing electric arc from heating and eroding the contacts of said male plug and my electric plug;

Second, to provide an electric plug of this class which employs spring and cam means for forcing the movable contacts thereof laterally into engagement with the prongs of a conventional male plug whereby intimate contact with said prongs is automatically and constantly maintained;

Third, to provide an electric plug of this class having a push button at one end thereof operatively connected with a pair of movable contacts arranged to grip the prongs of a male plug whereby lateral movement of said contacts may be readily accomplished when positioning my electric plug in connection with the prongs of a conventional male plug such as those in connection with electric irons, coffee pots or the like;

Fourth, to provide an electric plug of this class which is adapted to engage the prongs of a conventional male electric plug and is provided with spring loaded contacts which engage said prongs for constantly providing tension in connection therewith preventing arc between the prongs and said contacts;

Fifth, to provide an electric plug of this class which is very compact;

Sixth, to provide an electric plug of this class which is very simple to operate; and

Seventh, to provide an electric plug of this class which is very simple and economical of construction, efficient in its action and which will not readily deteriorate or get out of order.

With these and other objects in view, as will appear hereinafter, my invention consists of certain novel features of construction, combination and arrangement of parts and portions as will be hereinafter described in detail and particularly set forth in the appended claims, reference being had to the accompanying drawing and to the characters of reference thereon forming a part of this application in which:

Fig. 1 is a side elevational view of my electric plug; Fig. 2 is a view of one of the plates of my electric plug taken from the line 2—2 of Fig. 1 showing the movable contacts in connection therewith; Fig. 3 is a view of the other plate of

2

my electrical plug taken from the line 3—3 of Fig. 1 showing the stationary contacts in connection therewith; Fig. 4 is a transverse sectional view taken from the line 4—4 of Fig. 3; Fig. 5 is an enlarged fragmentary sectional view taken from the line 5—5 of Fig. 2.

Similar characters of reference refer to similar parts and portions throughout the several views of the drawing.

- 10 The plates 1 and 2, stationary contacts 3 and 4, movable contacts 5 and 6, push button 7, spring 8, connection shield 9, cord guides 10, cord 11 and the bolts 12 and 13 constitute the principal parts and portions of my electric plug.
- 15 The plates 1 and 2 are substantially flat members preferably made of electrical insulation material. The plate 1 is provided with slotted portions 1c in which the stationary contacts 3 and 4 are fixed by means of the bolts 3a and 4a, as shown in Fig. 4 of the drawings, to the opposite ends of which are connected the conductors 11a of the cord 11 which extends upwardly through the connection shield 9 and cord guide 10. These stationary contacts 3 and 4 align with recessed openings 1d in the plate 1 through which conventional electric plug prongs may be inserted when the plate 1 is in assembly with the plate 2 which is provided with similar openings 2a aligning with the movable contacts 5 and 6. These movable contacts 5 and 6 are slidably mounted in slotted portions 2d and are provided with shank portions 5a and 6a, respectively, which slide in the recessed portions 1e and 2e of the plates 1 and 2 which recessed portions are arcuate in cross section, as shown best in Fig. 4 of the drawing. Connected to the opposite ends of these shank portions 5a and 6a is the push button 7 engaged by the spring 8, the opposite end of which is fitted in the recess 2f of the plate 2 and the recess 1f of the plate 1 both of which recesses 2f and 1f are arcuate in cross section. The push button 7 is reciprocally mounted in recessed portions 2g and 1g of the plates 2 and 1, respectively, all as shown best in Figs. 2 and 3 of the drawing.
- 20 Electrically connected to the stationary contacts 3 and 4 are the bolts 3a and 4a to which the conductor wires 11a are electrically connected. The connection shield 9 is preferably made of insulation material and is held in place by the bolt 13 and the pins 2h, all as shown best in Fig. 1 of the drawing. The cord guide 10 is preferably made of convolutions of resilient wire and is fitted to the shield 9, as shown best in Fig. 1 of the drawing. The movable contacts 5 and 6 in connection with the plate 2 are similar in con-

- 50

struction and arrangement therefore the contact 6 as shown in Fig. 5 of the drawing will be hereinafter described in detail. As shown in Fig. 5 of the drawing, the recessed portion 2d is provided with an angularly inclined surface 2j engaged by the extending end 6b of the contact 6 adjacent the semi-circular in cross section opening portion 2a through which the prongs of the conventional male plug are inserted.

The operation of my electric plug is substantially as follows:

When in assembly, as shown in Fig. 1 of the drawing, the operator desiring to connect my electric plug with the prongs of a conventional male electric plug proceeds as follows: He first depresses the push button 7 which compresses the spring 8 and shifts the movable contacts 5 and 6 toward the openings 2a in the end of the plate 2. The end portions 6b of the movable contacts 5 and 6 pass downwardly on the inclined surface 2j of the recess 2d whereby lateral shifting of the contacts 5 and 6 is promoted permitting the prongs of the conventional male plug to be inserted between the contacts 5 and 6 and the contacts 3 and 4, respectively. After said insertion, the push button 7 is released permitting the spring 8 to force the movable contacts 5 and 6 longitudinally of the plate 2 forcing the same upwardly over the inclined surface 2j whereby lateral movement of said contacts 5 and 6 engages the same firmly with the opposite side of the prongs of the male plug from the stationary contacts 3 and 4. In this manner intimate contact with the prongs of a conventional male electric plug is always maintained.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In an electric plug of the class described, the combination of insulating means having longitudinal openings therein, a pair of movable contacts longitudinally slidable in said openings, a pair of stationary contacts adjacent said openings, resilient means tending to force said movable contacts longitudinally of the axis of said openings, said insulation means having inclined surface portions therein directed angularly and laterally of the longitudinal axis of said openings, said inclined surface portions being adjacent said openings, said movable contacts having surface

portions engageable with said inclined surface portions, whereby longitudinal movement of said contacts caused by said resilient means moves said movable contacts laterally of the axis of said openings toward said stationary contacts.

2. In an electric plug of the class described, the combination of insulating means having longitudinal openings therein, a pair of movable contacts longitudinally slidable in said openings, a pair of stationary contacts adjacent said openings, resilient means tending to force said movable contacts longitudinally of the axis of said openings, said insulation means having inclined surface portions therein directed angularly and laterally of the longitudinal axis of said openings, said inclined surface portions being adjacent said openings, said movable contacts having surface portions engageable with said inclined surface portions, whereby longitudinal movement of said contacts caused by said resilient means moves said movable contacts laterally of the axis of said openings toward said stationary contacts, electrical conductors in connection with said stationary contacts.

3. In an electric plug of the class described, the combination of insulating means having longitudinal openings therein, a pair of movable contacts longitudinally slidable in said openings, a pair of stationary contacts adjacent said openings, resilient means tending to force said movable contacts longitudinally of the axis of said openings, said insulation means having inclined surface portions therein directed angularly and laterally of the longitudinal axis of said openings, said inclined surface portions being adjacent said openings, said movable contacts having surface portions engageable with said inclined surface portions, whereby longitudinal movement of said contacts caused by said resilient means moves said movable contacts laterally of the axis of said openings toward said stationary contacts, electrical conductors in connection with said stationary contacts, a push-button connected with said movable contacts and positioned externally of said insulation means.
